V. ASHWORTH.

COAL CHUTE.

APPLICATION FILED JULY 7, 1913.

1,083,650.

Patented Jan. 6, 1914.

UNITED STATES PATENT OFFICE.

VINCENT ASHWORTH, OF PATERSON, NEW JERSEY.

COAL-CHUTE.

1,083,650.

Specification of Letters Patent.

Patented Jan. 6, 1914.

Application filed July 7, 1913. Serial No. 777,719.

To all whom it may concern:

Be it known that I, VINCENT ASHWORTH, a subject of the King of England, residing at Paterson, in the county of Passaic and 5 State of New Jersey, have invented certain new and useful Improvements in Coal-Chutes, of which the following is a specification.

The object of this invention is to provide 10 a chute for the discharge of coal from a wagon or other vehicle with a simple, inexpensive and durable cover for confining the coal and restraining the dust which is raised as the coal passes through the chute.

15 By my invention the ground between the vehicle and place of discharge of the chute is kept clear of scatterings of coal and coal dust and the driver's time need not be wasted in cleaning up after the coal is delivered.

20 In the accompanying drawing, fully illustrating the invention, Figure 1 is a perspective view of a chute provided with my improved cover or covering; Fig. 2 shows said cover extended, detached from the chute;

25 Fig. 3 is a plan view of the receiving end of the chute and of means preferably employed to keep the corresponding end of the cover in bell-mouth form or flaring; Fig. 4 is an end elevation of what is shown in

30 Fig. 1, looking toward the receiving end of the chute, the chute appearing in section; and Fig. 5 shows in side elevation what is seen in Fig. 3.

The chute *a* is of the usual construction, 35 having a bottom and two sides and being open at the top.

The cover *b* consists of an elongated piece of flexible sheet material, preferably heavy 40 duck, of generally tapering form, if, as is usual, the chute tapers, and provided with the straps *c* and *d* stitched or otherwise secured thereto and having buckles *e*, said straps projecting laterally at suitable intervals from said piece *b* so that when the

45 cover is laid over the chute with its wider end at the receiving or wider end of the chute they may be passed underneath said chute and buckled to secure the cover in place. The cover is somewhat wider than

50 the chute so that when in position its lateral edges extend down the sides of the chute and somewhat under the same. (Figs. 1 and 4). The end straps *c* are preferably unitary, or continuous from end to end, and 55 are stitched along the ends of the cover so as to form binding for its edges.

When the cover is in position it will be seen that it closes the chute at the top and so confines the coal and the dust therefrom in its passage through the chute. 60

At the receiving end of the chute the cover is preferably given a bell-mouth or flaring form so as to facilitate the admission of the coal. To accomplish this said end of the cover is made of the necessary width (for 65 instance, as illustrated in Fig. 2) and is kept in its open or extended form as follows: *f* is an arch consisting of two metallic strips *f'* *f''* overlapping each other and secured together by a screw *g* having a wing-

70 nut *h* and fitted to strip *f'* and penetrating a slot *i* in strip *f''*, the free ends of the strips being bent downwardly and then slightly inwardly, as at *j*, Fig. 4; a flanged keeper-piece *k'* may be utilized to keep the 75

strips alined. *k* designates clips or plates adapted to form clamps with the downwardly bent ends of the strips *f'* *f''*, each being arranged at the inner side of the corresponding strip; each clamp is completed 80

by the screw *l* penetrating the clip and corresponding strip and provided with a wing-nut *m*. Each clip has at its upper end a bent tongue *n* which is fitted to an eye *n'* in the corresponding strip. The strips *f'* *f''* may 85

have studs *o* to engage in eyelets *p* in the cover. Having fitted the arch to the chute as shown in Fig. 4, where each clamp appears as gripping a side of the chute and the arch is steadied by the squared lower ends 90

of its clips bearing against the floor of the chute while the inbent ends *j* of its strips take under the rebent flange *q* of the chute, the widened end of the cover is strapped around the arch, being kept in place by the 95 engagement of its studs with the eyelets *p*. The slot *i* in strip *f''* permits the arch to be laterally adjusted to suit chutes of different widths, as will be understood.

The cover being of flexible material it is 100 obvious that when not in use it may be folded and packed in small compass.

Having thus fully described my invention, what I claim and desire to secure by Letters Patent is:

1. In combination, with a chute having a bottom and two sides and open at the top, a covering for the open top of the chute consisting of an elongated piece of sheet material stretched over the top of the chute 110 and extending substantially from end to end thereof and having at each end unitary

straps forming bindings for said ends of the covering and each having means to secure said strap in embracing relation to the chute, substantially as described.

- 5 2. In combination, with a chute having a bottom and two sides and open at the top, a covering for the open top of the chute consisting of an elongated piece of sheet material stretched over the top of the chute and 10 extending substantially from end to end thereof and having means to removably secure said covering to the chute, and a rigid arch removably secured to the chute and maintaining one end of said covering in bell-mouth form, substantially as described.
- 15 3. In combination, with a chute having a

bottom and two sides and open at the top, a covering for the open top of the chute consisting of an elongated piece of sheet material stretched over the top of the chute and 20 extending substantially from end to end thereof and having means to removably secure said covering to the chute, and a rigid arch having clamps each gripping a side of the chute, substantially as described.

25

In testimony whereof I affix my signature in presence of two witnesses.

VINCENT ASHWORTH.

Witnesses:

JOHN W. STEWARD,
WM. D. BELL.
